UNITED STATES PATENT OFFICE.

HENRY C. NEEDHAM, OF LOS ANGELES, CALIFORNIA.

AUTOMATIC GRAVITY BOILER-FEEDER.

SPECIFICATION forming part of Letters Patent No. 658,728, dated September 25, 1900.

Application filed April 4, 1898. Serial No. 676,462. (No model.)

To all whom it may concern:

Be it known that I, HENRY CLAY NEEDHAM, a citizen of the United States, residing at Los Angeles, in the county of Los Angeles and State of California, have invented a new and useful Automatic Gravity Boiler-Feeder, of which the following is a specification.

The object of my invention is to provide improved means to do away with the use of a pump or inspirator for feeding water to boilers and to feed the water automatically by gravity-pressure, taking the water directly from a reservoir or from a water-main and causing the water to flow into the boiler automatically by the force of gravity.

In the operation of my invention steam from the boiler is applied inside the feed-reservoir to equalize the pressure in the reservoir and boiler, so as to allow the feed-water to flow freely from the feed-reservoir into the boiler, and I provide a supply-reservoir which is steam-tight and is connected with the feed-reservoir by a valved pipe to introduce the steam into the steam-supply reservoir from the feed-reservoir to equalize the steam-pressure between the supply-reservoir and feed-reservoir, and thus to allow water to flow from the supply-reservoir into the feed-reservoir through the valved pipe provided for that purpose.

An object attained by my invention is to avoid any discharge of steam into the open air from the boiler-feeding apparatus.

My invention comprises the various features, parts, and combinations hereinafter described and claimed.

The accompanying drawings illustrate my invention.

Figure 1 is a vertical mid-section of my newly-invented combined automatic gravity boiler-feeder applied to a boiler, fragments of which are shown. The pipes and valve mechanisms are shown intact. Fig. 2 is a vertical mid-section of the steam-shifting valve for the steam-supply pressure-pipe on line 2 2, Fig. 3. Fig. 3 is a sectional plan of the same on line 3 3.

My newly-invented apparatus comprises, in combination with the boiler A, a steam-tight feed-reservoir B, extending above the water-line of the boiler; a feed-pipe b, lead-

ing from the feed-reservoir to the boiler and provided with a check-valve b' to admit water to the boiler and prevent backflow; a steam-pipe b'', leading from the boiler to the feed-reservoir; a steam-tight supply-reservoir C, above the level of the feed-reservoir; a supply-pipe c, leading from the supply-reservoir to the feed-reservoir and provided with a check-valve c' to admit water by gravity from the supply-reservoir into the feed-reservoir and to prevent backflow; a supply-pressure steam-pipe c'', leading from the feed-reservoir into the supply-reservoir; a float-valve 5 to be operated by the water in the feed-reservoir and arranged to open and close the supply-pressure steam-pipe, and means for introducing water into the supply-reservoir when there is no steam-pressure therein. The feed-water pipe b is also provided with a globe-valve 1 between the check-valve b' and the boiler. The supply-pipe c is provided with a globe-valve 2 between the check-valve c' and the feed-reservoir. The supply-pressure steam-pipe c'' is provided with a globe-valve 75 3, and the steam-pipe b'' is provided with a globe-valve 4. These valves are necessary in starting the apparatus into operation to automatically feed the boiler; but after the automatic feeding apparatus has been put into operation the several globe-valves are not necessary to the continued operation; but the globe-valve 1 should be set to allow a flow of water into the boiler only slightly greater than sufficient to supply the evaporation.

The pipe d may be connected directly with the source of supply, as indicated by the pipe d'''. 9 indicates a globe-valve for shutting off the said pipe d''', and 10 indicates a globe-valve for closing the connection d² between a settling-tank (not shown) and the pipes d and d'''. 7 indicates a globe-valve in the pipe d between the check-valve d' and the pipe d². The purpose of these globe-valves, except hereinafter explained, is simply to cut off the respective pipes for repairs and other stoppages.

The float-valve 5 is especially constructed for the purpose of allowing the same to be readily operated against considerable steam-pressure by the lowering of the water-level in the feed-reservoir to open the supply-pres-

sure steam-pipe c'' , which is a steam-outlet pipe, to allow the steam to flow out of the feed-reservoir when the valve 5 is open.

5' is an externally and internally threaded collar screwed onto the end of the outlet-pipe c'' .

c^3 is a valve-seat screwed into the collar.

c^4 is a guide fixed to the upper end of the valve-seat and extending thereacross.

10 c^5 is an annular valve seated in the valve-seat.

5' is a vent-valve for closing the central opening of the annular valve and provided with a stem 5'', extending through the guide

15 c^4 and provided with stops 5''' 5'''' to engage the annular valve to move the same from and toward the valve-seat, said vent-valve being arranged to provide a vent through the annular valve when the vent-valve is drawn 20 away from the annular valve. For this purpose the vent-valve is preferably provided with a small steam-passage 52, having its discharge-outlet above the annular valve c^5 and having its mouth or inlet 53 at such a 25 point that it will be closed by the annular valve when the vent-valve is seated against the annular valve.

20 c^6 indicates a cap screwed onto the collar c^2 and provided with steam-inlet c^7 to admit 30 steam to the valves and arranged to form a stop, as at c^8 , to limit the movement of the annular valve.

Suitable means are provided for moving the vent-valve to operate the annular valve.

35 The means which I have shown comprise a bifurcated float-lever 54, pivoted to a support 55, depending from and forming a part of the cap c^6 .

56 indicates the pivot of the float-lever.

40 57 indicates a slot in the lever 54, and 5''''' indicates a pin carried by the vent-valve 5' and working in the slot 57.

58 indicates an adjusting-screw in the lever 54 and extending against the lower end

45 of the vent-valve 5', so that the play of the lever 54 with relation to the pin 5''''' can be regulated.

I will now describe the operation of my invention.

50 Starting with an empty boiler, the globe-valves 1, 2, 3, 4, 7, and 10 will all be opened and the water allowed to flow into the boiler until the boiler is full to the water-line. The water flows through the supply-reservoir and 55 the feed-reservoir and thence into the bottom of the boiler by gravity. When the water in the boiler has reached the water-line, the globe-valves 2 and 3 will be closed and steam will be raised until the steam-pressure exceeds the pressure of the water through the pipe c .

60 Then the globe-valves 2 and 3 are opened and the water flows through pipe c into the feed-reservoir B until it causes the float-valve 5 to close. The steam-pressure 65 in feed-reservoir B then sets the check-valve c' , and so long as the steam-pressure in the feed-reservoir is not relieved the water is

prevented from flowing from the supply-reservoir C into the feed-reservoir B. When the water in the feed-reservoir is above the 70 water-line of the boiler, the float-valve 5 holds the supply-pressure pipe c'' closed.

The globe-valve 1 will then be set to allow a flow of water slightly greater than that which is necessary to supply evaporation from the 75 boiler, and the water will slowly seek its level in filling the boiler as desired.

The pressure of steam on the water in the feed-reservoir counterbalances that on the water in the 80 boiler, so that the water is free to flow from the feed-reservoir to the boiler by gravity as though in the open air.

When the level of the water in the feed-reservoir falls to the water-line of the boiler, the valve-lever 54 has fallen sufficiently to pull down upon the 85 pin 5'''', thus pulling down upon the vent-valve 5' and slightly withdrawing it from its seat in the annular valve c^5 , and immediately this has been accomplished the steam rushes into the small vent-opening 53, thus admitting 90 steam into the pipe c'' , and thus allowing the weight of the lever 54 and its float and the weight of the vent-valve 5' and the annular valve c^5 to all operate to draw the valve c^5 from its seat and allow the steam to 95 flow unobstructed into the pipe c'' and into the supply-reservoir C, thus applying to the top of the water in the supply-reservoir a pressure corresponding to the pressure in the boiler.

This sets the check-valve d' and 100 equalizes the pressure on both sides of the check-valve c' and allows the water from the supply-reservoir to open the check-valve c' and flow freely into the feed-reservoir until the level of the water in the feed-reservoir 105 has been raised sufficiently to again cause the float-valve to close, thus shutting off the steam-pressure from the supply-reservoir C, thus again setting the check-valve c' and allowing the check-valve d' to again open to 110 fill the supply-reservoir.

By preference the supply-pipe c is a two-inch pipe, so that the feed-reservoir will quickly fill; but it will be understood that throughout the operation above described the 115 flow of water into the boiler through the pipe b will be uninterrupted provided the level of the water in the boiler is below that of the water in the feed-reservoir.

The feed-reservoir is preferably provided 120 with a water-glass F somewhat longer than the water-glass F' of the boiler for the reason that the variation of the water-level in the feed-reservoir is preferably greater than that for the boiler.

125 By means of the arrangement which I have shown for the valve 5 the several parts can be very conveniently assembled and the valve cheaply and easily constructed. The opening for the vent-valve in the annular valve is 130 preferably about one-quarter of an inch, and the vent-opening through the valve about one-sixteenth of an inch, more or less, and the stem of the valve preferably fits the opening

in the annular valve closely, and the vent-valve sets steam-tight into the annular valve when the vent-valve is pushed into place, and the lower stop 5''' is a part of the vent-valve and serves to close the annular valve as well as to carry it.

The weight of the float is made sufficiently great to be ample to overcome any steam-pressure which will be applied to the quarter-inch area of the vent-valve, so that when the float is unsupported by the water it will invariably withdraw the vent-valve to open the vent-passage 52 to apply the steam-pressure to the upper side of the annular valve, and the stop 5''' is arranged to be brought down against the top of the annular valve, thus to add its weight and the weight of the float and lever to force the annular valve from its seat.

In setting the device the adjusting-screw 58 will be set at such a point as to allow only that play of the lever which is desirable without operating the valve.

After the apparatus has once been set into operation it will continue to operate so long as the steam-pressure remains up. When the boiler is allowed to cool, it is to be understood that the globe-valves must be closed, and when it is again desired to raise steam the operation of starting the apparatus into use, as hereinbefore described, must be repeated.

Now, having described my invention, what I claim as new, and desire to secure by Letters Patent, is—

1. The combination with a boiler, of a steam-tight feed-reservoir extending above the water-level of the boiler; a feed-water pipe leading from said reservoir into the boiler and provided with a check-valve to admit water into the boiler and prevent backflow; a steam-pipe leading from the boiler to the feed-reservoir; a steam-tight supply-reservoir above the feed-reservoir; a supply-pipe leading from the supply-reservoir to the feed-reservoir and provided with a check-valve to admit water by gravity from the supply-reservoir into the feed-reservoir and to prevent backflow; the supply-pressure steam-pipe leading from the feed-reservoir into the supply-reservoir; a float-valve to be operated by the water in the feed-reservoir and arranged to open and close the supply-pressure steam-pipe; and valved means for introducing water into the supply-reservoir when there is no steam-pressure therein.

2. A gravity boiler-feeder comprising a steam-tight feed-reservoir extending above the water-level of the boiler; a feed-pipe leading from the feed-reservoir to the boiler and

provided with a check-valve to admit water to the boiler and prevent backflow and also 60 provided with a globe-valve between the check-valve and the boiler; a steam-pipe leading from the boiler to the feed-reservoir and provided with a globe-valve; a steam-tight supply-reservoir above the feed-reservoir; a 65 supply-pipe leading from the supply-reservoir to the feed-reservoir and provided with a check-valve to admit water by gravity from the supply-reservoir into the feed-reservoir and to prevent backflow and said pipe also 70 being provided with a globe-valve between the feed-reservoir and said check-valve; a supply steam-pipe leading from the feed-reservoir into the supply-reservoir and provided with a globe-valve; a float-valve to be operated by 75 the water in the feed-reservoir and arranged to open and close the supply-pressure steam-pipe; and a water-supply pipe with a check-valve to admit water into the supply-reservoir when there is no steam-pressure therein, 80 and to close against the steam-pressure when steam is admitted to the supply-reservoir.

3. The combination of an outlet-pipe; a collar screwed onto the end of the pipe; a valve-seat screwed into the collar; a guide clamped 85 between the valve-seat and the end of the pipe and extending across the pipe; an annular valve seated in the valve-seat; a vent-valve for closing the central opening of the annular valve and provided with a stem extending through the guide and provided with stops to engage the annular valve to move the same, said vent-valve being arranged to provide a vent through the annular valve when the vent-valve is drawn away from the 95 annular valve; a cap screwed onto the collar and provided with steam-inlet to admit steam to the valves and arranged to form a stop to limit the movement of the annular valve; and means for moving the vent-valve to operate 100 the annular valve.

4. The combination of a pipe; a collar screwed onto the end of the pipe; a valve-seat screwed into the collar; an annular valve seated in the valve-seat; a vent-valve to close 105 the opening in the annular valve and provided with stops to limit its movement with relation to the annular valve; a cap screwed onto the collar and provided with inlet admitting to the valve; and a float-lever pivoted 110 to a support and to the vent-valve for operating said valves.

H. C. NEEDHAM.
